UNITED STATES PATENT OFFICE.

WILLIAM ROBERT McCLUNEY, OF WARRENSBURG, MISSOURI.

TACK AND BRAD DRIVER.

Application filed September 9, 1927. Serial No. 218,479.

The present invention relates to an instrument which is designed to enable the worker to use only one hand in the process of inserting tacks and small brads.

5 An important object of the invention resides in the provision of an instrument of this nature with a structure consisting of elements which are easy to handle and manipulate, are arranged in a convenient and 10 compact manner, and otherwise thoroughly efficient and reliable in use and operation.

A further important object of the invention resides in the provision of an instrument of this nature which is simple in construction, which is easy to assemble and disassemble, capable of being manufactured at a low cost, and otherwise well adapted to the purpose for which the same is designed.

With the above and numerous other objects in view as will appear as the description proceeds, the invention resides in certain novel features of construction, and in the combination and arrangement of parts as will be hereinafter more fully described and 25 claimed.

In the drawing:—

Figure 1 is an elevation of the instrument embodying the features of my invention,

30 Figure 2 is a similar view taken at right angles to that shown in Figure 1,

Figure 3 is a longitudinal section therethrough,

35 Figures 4 and 5 are transverse sections taken substantially on the lines 4—4 and 5—5 respectively of Figure 1.

Figure 6 is a sectional elevation showing portions of the device with parts for use with brads.

Referring to the drawings in detail it will 40 be seen that the numeral 5 denotes a stock or handle shaped to conveniently fit in the hand having a restricted neck portion 6. This stock or handle is provided with a bore 7 having a reduced portion 8. An elongated 45 cylindrical casing 9 is provided with threads 10 intermediate its ends and extends up into the smaller portion of the bore 8 to terminate within the bottom of the bore 7. The upper portion of this casing within the bottom of the bore 7 is formed with a bayonet slot 50 opening or the like 11. A permanent magnet 12 is threadedly engaged on the casing 8 as at 10 and has its ends provided with pins 13 of magnetic material extending through 55 the casing 9. A plunger 14 is slidable through the casing to engage the pins 13 and

the upper end of this plunger 14 is threadedly engaged as at 15 with a shank 16 having a knob 17 adapted to fit in the upper end of the handle 5. A spring 19 is disposed 60 about the shank 16 and impinges against the bottom of the bore 7 and the knob 17 to normally hold the knob 17 in the dotted line position shown in Figure 3. This knob may be forced down to the full line position 65 shown in Figure 3 so that a pin 20 on the plunger may be engaged in the bayonet slot 11 so as to hold the parts in this position.

The casing should be constructed of 70 wrought or non-magnetic metal. The iron or steel pins 13 are used for the purpose of conducting lines of force to the plunger. The knob may be constructed of hard rubber and the shank may be made of hard wood. 75 The spring should be comparatively weak.

In using this instrument it is held in the palm of the hand with the neck fitted between the second and third fingers. Thus when the plunger is released the hand is 80 spread apart. This draws the tack inside the casing attached to the point of the plunger. To insert the tack or brad the plunger is forced down and engaged by the palm of the hand with the instrument still 85 in the position as described above. With the magnetized plunger down the head of the tack or brad is attached and if the instrument is manipulated as has been previously instructed, the worker will have no trouble 90 in becoming efficient with the tool.

In Figure 6 a slight modification is provided for use with brads. Parts 9', 10' and 13' are similar to aforementioned parts 9, 10 and 13, respectively. A sleeve 30 is held 95 in place by screw 22 extending into opening 31. A rod 32 extends through the sleeve 30. The sleeve 30 and rod 32 take the place of the plunger 14, the rod functioning as the plunger.

100 It is thought that the construction, operation, utility, and advantages of the invention will now be quite apparent to those skilled in this art without a more detailed description thereof. The present embodiment of the invention has been disclosed in detail merely by way of example since in actual practice it attains the features of advantage enumerated as desirable in the statement of the invention and the above description. It will be apparent that changes 105 in the details of construction, and in the

combination and arrangement of parts may be resorted to without departing from the spirit or scope of the invention as herein-after claimed or sacrificing any of its advantages.

Having thus described my invention, what I claim as new is:—

1. An instrument of the class described comprising a handle having a bore extending therethrough, a cylindrical casing extending into the bore, a plunger slideable through the casing, means for magnetizing the plunger, a shank attached to the plunger, a knob on the end of the shank, and a spring 10 associated with the shank and the knob to normally hold the plunger retracted in the casing.

2. An instrument of the class described comprising a handle having a bore formed in a relatively large section and a relatively small section, a cylindrical casing extending into the smaller section and terminating within the bottom of the larger section, said termination of the casing being provided 25 with a bayonet slot, a plunger slideable through the casing and having a laterally extending pin adapted to be engaged with the bayonet slot, a shank engaged on the plunger within the larger section of the bore, a knob on the shank, a spring engaged on the larger section of the bore about the shank impinging against the bottom of the larger section of the bore and the knob, and means for magnetizing the plunger.

3. An instrument of the class described comprising a handle having a bore formed in a relatively large section and a relatively small section, a cylindrical casing extending

into the smaller section and terminating within the bottom of the larger section, said termination of the casing being provided 40 with a bayonet slot, a plunger slideable through the casing and having a laterally extending pin adapted to be engaged with the bayonet slot, a shank engaged on the plunger within the larger section of the bore, 45 a knob on the shank, a spring engaged on the larger section of the bore about the shank impinging against the bottom of the larger section of the bore and the knob, and means for magnetizing the plunger.

4. An instrument of the class described comprising a handle having a bore formed in a relatively large section and a relatively small section, a cylindrical casing extending 50 into the smaller section and terminating within the bottom of the larger section, said termination of the casing being provided with a bayonet slot, a plunger slideable through the casing and having a laterally extending pin adapted to be engaged with the bayonet slot, a shank engaged on the plunger within the larger section of the bore, 55 a knob on the shank, a spring engaged on the larger section of the bore about the shank impinging against the bottom of the larger section of the bore and the knob, and means for magnetizing the plunger, said means comprising a permanent magnet, means for engaging the permanent magnet on the casing, and means extending through the casing 60 in contact with the poles of the permanent magnet.

In testimony whereof I affix my signature.
WILLIAM ROBERT McCLUNEY.
